UNITED STATES PATENT OFFICE.

ALEXANDER ROEGER, OF NEW YORK, N. Y.

HANDLE AND CASE.

SPECIFICATION forming part of Letters Patent No. 239,115, dated March 22, 1881.

Application filed January 25, 1881. (No model.)

To all whom it may concern:

Be it known that I, ALEXANDER ROEGER, a citizen of the United States, residing at New York city, in the county of New York and 5 State of New York, have invented certain new and useful Improvements in Air-Tight Tool Handles and Case; and I do hereby declare the following to be a full, clear, and exact description of the invention, such as will enable 10 others skilled in the art to which it appertains to make and use the same, reference being had to the accompanying drawings, and to letters or figures of reference marked thereon, which 15 form a part of this specification.

The object of my invention is to form a two-part air-tight handle and a convenient fastening for tools used in cutting, puncturing, and similar purposes in mechanical operations, for 20 toilet and pocket articles for special convenience in traveling, and for instruments used by professional men, which can be quickly disengaged from the holder or handle and another substituted, or, when separated, conveniently packed in a small compass in the handle for 25 future use.

Referring to the drawings, in which similar letters of reference indicate corresponding parts, Figures 1 and 2 represent the two parts of the handle, the first showing the grooves 30 along its sides, the angular fastening, and space for containing tools or articles desired. The second represents the opposite part of the handle, showing the small flanges intended to glide into the grooves of the first part, for 35 securing the two together, and also showing the plate opposite the fastening in the first part and space for containing articles in it. Fig. 3 shows one of the tools or articles in position in the fastening; also shows the handle for 40 containing articles. Fig. 4 shows the tool or article reversed in its fastening. Fig. 5 shows the parts of the handle united, and having one of the articles reversed to fill the fastening, and thereby produce an air-tight case. 45 Fig. 6 shows the fastening detached. Fig. 7 shows the shank of the tool or article with its recesses corresponding with the fastening in the handle.

A B are the two hollow halves of the handle, having the receptacles *a* and *b*, respectively. A has grooves *a'* *a'* along its sides,

into which flanges *b'* *b'* glide, and may be held closed by catch *e* or other suitable means, securing the two parts together in the strongest manner possible, thus forming the complete handle and securely holding the tool in its angular fastening when the case is closed, as will be more fully explained hereinafter. The part A has in one end the right-angular fastening C, in the peculiar form shown, consisting of the right-angular projection *c*, presenting shoulders *c'* *c'*, and having a thin jaw-plate, *c*², extending the length of the fastening.

The different tools or articles desired to be used in the fastening are formed with angular recesses *d* *d*, having shoulders *d'* *d'*, said recesses corresponding with the projections *c* of the fastening, so that the tool or articles may be fitted closely into the fastening for use, as shown in Fig. 3, or placed in the reverse position shown in Fig. 4. The square shoulders of the articles bearing against the square shoulders of the fastening, in conjunction with the jaw-plates *b*² and *c*², make the strongest 75 and most secure bearing to resist any strain or twist that is possible. The jaw-plates *b*² and *c*² being thin and short, articles may extend beneath them, and are prevented from falling out by them when the case is open, as 80 well as allowing the full length of the case to accommodate the articles contained. It is believed that the reversible feature and the secure fastening are both entirely new and very valuable in such cases.

It is obvious when the smaller tools or articles are packed in the respective sides of the handle, and one of the tools or articles are reversed in its fastening and the case closed by gliding them together, that the reversed 90 position of one of the articles in its fastening will not only protect that particular article better than heretofore, but that it will also exclude the moisture and dust from all the other contents of the handle by stopping up 95 the only aperture through which the dust or moisture could pass, while at the same time allowing the full length of the handle to accommodate the longer articles.

It is also obvious that this result is very desirable with various cutlery, toilet articles, small mechanical tools, and surgical or dental

instruments, for which this handle is peculiarly adapted, inasmuch as heretofore no such protection has been afforded with the same convenience.

- 5 It is obvious, too, that various pocket "companions" may be formed out of the elements of this device, among which may be named: mechanic's companion, containing small tools, which he might wish to always have with him; 10 the lady's and gentleman's companion, filled with such articles as would be convenient or needed by each, especially in traveling; the dentist's or surgeon's companion, in which might be placed the various instruments desired always to have in the pocket; and last, but not least, the "toilet companion," for either home or traveling, in the arrangement of which it is thought best to fill the part B with fine tooth-powder or other dentifrice, and by moistening the same reduce it to the cake form, and having a tooth-brush reversed in the other part, when not in use, but which may be taken out and applied to the "caked" dentifrice, when desired to be used, with less loss of the dentifrice, with greater convenience, and provide greater protection to the brush than is the case in any device now in use.

The various forms of this device may be made out of any suitable material, such as

- 15 30 the various metals, celluloid, rubber, ivory, pearl, hard woods, &c., and may be made in an oval, elliptical, or other suitable form, in various ornamental designs.

Having thus fully described my invention,

what I claim as new, and desire to secure by 35 Letters Patent of the United States, is—

1. A two-part handle, being secured together by grooves *a'* and flanges *b'*, in combination with the described right-angular fastening for instruments or articles desired to be 40 used in said handle, substantially as and for the purpose set forth.

2. In a tool or instrument handle, the two parts A B, having the right-angular fastening C; said fastening being formed substantially 45 as described, in combination with tools or instruments with shanks formed to correspond with and fit into said fastening, either in the extended or reversed position, whereby air and moisture are practically excluded from the 50 contents of the handle, substantially as and for the purpose set forth.

3. As a new article of manufacture, the two-part handle A B, having the right-angular fastening C, said fastening formed substantially as described, in combination with a tooth-brush with its shank formed to correspond with and fit into said fastening, whereby air and moisture are practically excluded from the 55 contents of the handle, substantially as and for the purpose set forth.

In testimony whereof I hereto affix my signature in presence of two witnesses.

ALEXANDER ROEBER.
